UNITED STATES PATENT OFFICE.

FORD ADDISON MANSELL, OF TRENTON, CANADA.

WINDOW-SCREEN.

SPECIFICATION forming part of Letters Patent No. 739,553, dated September 22, 1903.

Application filed December 4, 1902. Serial No. 133,844. (No model.)

To all whom it may concern:

Be it known that I, FORD ADDISON MANSELL, merchant, a subject of the King of Great Britain, residing in the town of Trenton, in the county of Hastings, in the Province of Ontario, Canada, have invented certain new and useful Improvements in Window-Screens, of which the following is a specification.

10 My invention relates to improvements in window-screens; and the object of my invention is, first, to design a screen that can be used in connection with all kinds of windows; secondly, to design a screen that can be attached to the window-sash and permit same to be raised up and down without necessitating the removal of the window-screen therefrom, and, thirdly, to design a neat, cheap, and compact window-screen; and it consists, 15 broadly, in combining with a window-frame and sash for same a window-screen comprising a spring-controlled roller, two brackets in which said roller is journaled, a suitable netting wound around said roller, two plates secured at their inner ends to said brackets and above said roller and netting thereon, their inner edges being wide enough apart to permit the netting to pass therebetween, and means secured to the free end of said netting 20 by means of which the netting is secured to the under side of a window-sash.

In carrying out my invention I form a suitable chamber in the window-sill immediately below the window-sash and place my window-screen therein. There are other details of construction, that will be hereinafter more particularly explained.

Figure 1 is a general perspective of my window-screen. Fig. 2 is an enlarged cross-section through my window-screen and supporting parts for same, showing same attached to a window-sash, which is also shown in section. The section in Fig. 2 through the sash and the attaching means for the window-screen is taken on the line *a b*, Fig. 3, looking in the direction indicated by arrow. Fig. 3 is a section on the line *e f*, Fig. 2, looking in the direction indicated by arrow. Fig. 4 is a vertical section on the lines *c d*, Fig. 1, looking in the direction indicated by arrow. Fig. 5 is a vertical section through one end of the spring-controlled roller. Fig. 6 is a

plan view of a suitable device used for locking the window-screen to the window-sash. Fig. 7 is a cross-section through the head of 55 the window-screen, showing one means by which the netting may be secured thereto.

In the drawings like letters of reference indicate corresponding parts in each figure.

A is any suitable roller mounted at one end 60 in the bracket B by a spindle C and mounted at its other end in the bracket D by the spindle E. I preferably use a hollow roller for manufacturing my window-screen. Contained within the roller A and at one end of 65 same is a suitable spring F, which is secured at one end *f* to said roller and is secured at the other end at *a* to a disk *c*, which is suitably keyed to the spindle C. *b* is a cap inclosing this end of the roller. 70

Keyed to the spindle C at the outer side of the bracket B is a pinion G, which meshes with a ratchet-wheel H, keyed to a stud I, suitably journaled in the bracket B and in the casing J, which incloses these parts. The 75 said casing is suitably secured to the outside of the bracket B. The spindle C also has bearing in said casing. The inner end *i* of the stud I is suitably formed so that a key may operate therewith for the purpose of 80 regulating the tension of the spring F, as will be understood. The tendency of the spring F is of course to rotate the roller A.

Suitably pivoted to the bracket B is a pawl L, which engages with the ratchet-wheel H 85 to prevent movement of same in one direction. I essentially use a spring in connection with my roller and use suitable means for preventing said spring from being unduly unwound, and although I have minutely described the parts for this purpose I do not confine myself to same, as many different devices could be designed for this purpose without departing from the spirit of my invention. 90

Fitting within the opposite end of the roller A is any suitable thimble M, provided with a cap N. Held in the inner end *m* of said thimble and said cap N is the spindle E. Suitably secured to this spindle is a spring O. It will be understood that as soon as the roller is 100 placed in position the spring O will force the spindle E into its bearing in the bracket D.

o is any suitable disk secured within the thimble M for giving additional bearing to

the spindle E. I preferably use a spring-controlled spindle at this end of the roller for the purpose before described, but do not confine myself to the construction herein shown and described. It will be noticed that the cap N has the same external diameter as the roller A, thus providing an even surface for the netting to be wound around.

P is the window-sill, which is hollowed out 10 directly beneath the sash, as shown at Q.

R represents the usual guides between which the sash S operates.

T is any suitable netting wound around the roller A. At the outer end of this netting is 15 secured a plate U, which is of the same width and length as the sash S. It will of course be understood that the roller A and its netting are also of the same width as the sash. In the construction shown in the drawings 20 the plate U is provided with two downwardly-projecting ribs V and V', between which the said netting is held in any suitable manner. I inclose the roller A and its netting within the space Q as much as possible by means of 25 two suitably-shaped plates v and u, which are suitably secured in place to the window-sill and also to the brackets D and B. Between the inner edges of these plates it will be noticed that there is a space w, in which 30 operates the netting. When the sash S is lowered to its lowest point, it forces the plate U down upon the plates v and u, thus passing the ribs V and V' into the space w. It will be noticed that the outer plate v is curved 35 downwardly to correspond with the lower shape of the window-sash. This construction prevents any water from getting down onto the netting. In case the plate v is a particularly long one I support same at its 40 under side by any suitable brackets W, suitably secured to the window-sill.

In order to detachably secure the suitable plate U to the bottom of the window-sash, I 45 employ the following construction: I drill a hole up through the plate U and insert therein the stud 3. I pierce the ribs V and V' with a hole 4 for the purpose of enabling me to place the stud 3 in place. Suitably secured to the upper end of the stud 3 is a head 50 5. Countersunk in the under side of the sash S is any suitable plate 6, provided with a slot 7. When it is desired to lock the screen to the sash S, the head 5 of the stud 3 is passed through the slot 7 and turned sidewise, as 55 shown in Fig. 3, thus engaging with the plate 6.

The sash 7 is recessed, as shown at 8, in order to permit of the movement of the head 5. I move the stud 3 by means of any suitable pin 9, secured thereto, which operates 60 in a slot 10, formed in the rib V'. Although I have described minutely this means for securing the screen to the sash, I do not confine myself to same, as different devices could be designed for this purpose without departing from the spirit of my invention.

As the roller A is always operated by the spring F to wind up the netting, it will be

understood that the same will always be held taut. A great advantage derived from using my screen is that no matter in what position 70 the window-sash may be in the screen is always in position for use. When once my window-screen is placed in position, it is intended that same shall not ordinarily be unlocked from the sash. As the sash can be 75 raised up and down freely, it will be seen that it will not be necessary to unlock the screen therefrom.

It will be understood from the specification and claims that I may dispense altogether 80 with the use of the plates v and u in connection with the other elements of my window-screen without departing from the spirit of my invention.

What I claim as my invention, and desire 85 to secure by Letters Patent, is—

1. A window-screen comprising a spring-controlled roller; two brackets in which said roller is journaled; a suitable netting wound around said roller; two plates secured at their 90 ends to said brackets and above said roller and netting thereon, the inner edges of said plates being wide enough apart to permit the netting to pass therebetween, one of said plates being wider than the other; a plate secured to the free end of said netting; one or more studs held in said plate and having their outer ends bent at right angles and extending above the upper surface of said plate and means upon the sash to engage the same. 100

2. A window-screen comprising a roller; two brackets in which said roller is journaled; a spindle held in one end of said roller; a spring secured to said roller and said spindle; a pinion keyed to said spindle and on the 105 outer side of the bracket B; a ratchet-wheel journaled in said bracket and meshing with said pinion; a pawl engaging with said ratchet-wheel, the said ratchet-wheel being operated to regulate the tension of said spring; 110 a netting wound on said roller; two plates secured at their ends to said brackets above said roller and netting thereon, the inner edges of said plates being wide enough apart to permit the netting to pass therebetween, 115 one of said plates being wider than the other; a plate secured to the free end of said netting; one or more studs held in said plate, and having their outer ends bent at right angles and extending above the upper surface 120 of said plate and means upon the sash to engage the same.

3. A window-screen comprising a roller; two brackets in which said roller is journaled; a spindle held in one end of said roller; a 125 spring secured to said roller and said spindle; a pinion keyed to said spindle and on the outer side of the bracket B; a casing secured to the outer side of said bracket B; a ratchet-wheel incased thereby and journaled therein 130 and in said bracket and meshing with said pinion; a pawl engaging with said ratchet-wheel, the said ratchet-wheel being operated to regulate the tension of said spring; a net-

ting wound on said roller; two plates secured at their ends to said brackets above said roller and netting thereon, the inner edges of said plates being wide enough apart to permit the 5 netting to pass therebetween, one of said plates being wider than the other; a plate secured to the free end of said netting; one or more studs held in said plate, and having their outer ends bent at right angles and extending above the upper 10 surface of said plate, and designed to be engaged with said means in the under side of said sash to engage the same.

4. A window-screen comprising a roller; two brackets in which said roller is journaled; a spindle held in one end of said roller; a 15 spring secured to said roller and said spindle; a pinion keyed to said spindle and on the outer side of said bracket B; a ratchet-wheel journaled in said bracket and meshing with said pinion; a pawl engaging with said 20 ratchet-wheel, the said ratchet-wheel being operated to regulate tension on said spring; a spring-controlled spindle held in the other end of said roller and designed to be journaled in the bracket D; a netting wound on 25 said roller, and means for securing the free end of said netting to the under side of a sash.

5. In combination with a window-sill provided with a chamber directly beneath the window-sash, and window-sash operating in 30 connection with said window-sill, of a window-screen, comprising a roller; two brackets in which said roller is journaled; a spindle held in one end of said roller; a spring secured to said roller and said spindle; a pinion keyed 35 to said spindle and on the outer side of the bracket B; a ratchet-wheel journaled in said bracket and meshing with said pinion; a pawl engaging with said ratchet-wheel, the said ratchet-wheel being operated to regulate the 40 tension of said spring; a netting wound on said roller, and means for securing the free end of said netting to the under side of the sash.

6. In combination with a window-sill provided with a chamber directly beneath the window-sash; window-sash operating in connection with said window-sill, and means secured in the under side of said window-sash to which the free end of a netting may be secured, of a window-screen comprising a roller; two brackets in which said roller is journaled; a spindle held in one end of said roller; a spring secured to said roller and said spindle; a pinion keyed to said spindle and on the outer 55 side of the bracket B; a casing secured to the outer side of said bracket B; a ratchet-wheel inclosed in said casing and journaled therein and in said bracket and meshing with said pinion; a pawl engaging with said ratchet-wheel, the said ratchet-wheel being operated 60

to regulate the tension of said spring; a netting wound on said roller; a plate provided with two downwardly-projecting ribs between which is secured the free end of said netting, the said plate being the same length as said 65 roller, and one or more studs held in said plate and having their outer ends bent at right angles and extending above the upper surface of said plate, and designed to be engaged with said means in the under side of 70 said sash to attach the netting to the sash.

7. In combination with a window-sill provided with a chamber directly beneath the window-sash; window-sash operating in connection with said window-sill; the outer side 75 of said window-sash being provided with one or more recesses, and a corresponding number of slotted plates secured to said window-sash over said recesses, of a window-screen comprising a roller; two brackets in which said roller is journaled; a spindle held in one end of said roller; a spring secured to said roller and said spindle; a pinion keyed to said spindle and on the outer side of the bracket B; a casing secured to the outer side of said 80 bracket B; a ratchet-wheel inclosed in said casing and journaled therein and in said bracket and meshing with said pinion; a pawl engaging with said ratchet-wheel, the said ratchet-wheel being operated to regulate the 85 tension of said spring; a netting wound on said roller; a plate, provided with two downwardly-projecting ribs between which is secured the free end of said netting, the said plate being the same length as said roller, and one or more studs held in said plate and having their outer ends bent at right angles 90 and extending above the upper surface of said plate and designed to be engaged with said slotted plates so as to attach the netting to 95 the sash.

8. A window-screen comprising a spring-controlled roller; two brackets in which said roller is journaled; a suitable netting wound around said roller; two plates secured at their 105 ends to said brackets and above said roller a netting thereon, the inner edges of said plates being wide enough apart to permit the netting to pass therebetween, one of said plates being wider than the other, and means secured to the free end of said netting by 110 means of which the netting is secured to the under side of a window-sash.

In testimony whereof I have signed my name to this specification in the presence of 115 two subscribing witnesses.

FORD ADDISON MANSELL.
